UNITED STATES PATENT OFFICE.

LOUIS WEBER, SR., OF PHILADELPHIA, PENNSYLVANIA.

DESIGN FOR HOSIERY.

Application filed December 29, 1928. Serial No. 29,441. Term of patent 14 years.

To all whom it may concern:

Be it known that I, LOUIS WEBER, Sr., a citizen of the United States, residing at Philadelphia, in the county of Philadelphia and State of Pennsylvania, have invented a new, original, and ornamental Design for Hosiery, of which the following is a specification, reference being had to the accompanying drawing, forming a part thereof.

The figure is a side elevation of a stocking, with the top thereof partly broken away, embodying my new design.

The design shown is applied to both sides of the stocking.

I claim:

The ornamental design for hosiery as shown and described.

LOUIS WEBER, Sr.
